UNITED STATES PATENT OFFICE.

WILLIAM F. SPINNEY, OF READING, MASSACHUSETTS.

METHOD OF SECURING BUTTONS TO MATERIALS.

SPECIFICATION forming part of Letters Patent No. 268,745, dated December 5, 1882.

Application filed August 25, 1882. (No model.)

To all whom it may concern:

Be it known that I, WILLIAM F. SPINNEY, of Reading, in the county of Middlesex and State of Massachusetts, have invented certain 5 Improvements in the Method of Securing Buttons and other Articles to Materials, of which the following is a specification.

This invention has for its object to provide improved means for attaching buttons and 10 other like articles to the flexible material on which they are to be used by means of a pellet or body of compressible metal or other suitable material inserted with a portion of the material into or through an orifice in the button 15 and upset while so inserted.

The invention consists in the improved method hereinafter described, and in a button or other article secured by my improved method, 20 all of which I will now proceed to describe and claim.

Of the accompanying drawings, forming a part of this specification, Figures 1 and 2 represent sectional views showing my improved method of attaching buttons. Fig. 3 represents a sectional view showing a different form 25 of button. Fig. 4 represents a sectional view showing a glove-fastening. Figs. 5 and 6 represent views showing a button and a modification of the compressible pellet or body. Fig. 30 7 represents a button adapted to be fastened by my method.

In carrying out my invention I take a button, A, or other article having an orifice, A', and draw a part of the material B to which 35 the button is to be attached through said orifice in the form of a pocket, P, as shown in Fig. 1. In this pocket I place a pellet or body, C, of lead or other suitable material, and then by the use of suitable tools I compress and 40 upset the pellet above the button, as shown in Fig. 2, so that it cannot pass through the orifice in the button, but remains with the pocket upon the opposite side of the button from the material, and forms a connection between the 45 button and material which can only be severed by the breaking away of the latter. The upset end of the pellet or body C is of course covered by the material which appears as a rounded projection on the exposed side of the 50 button and gives a very neat effect. The orifice A' in the button may extend entirely through the button, as shown in Figs. 1 and 2, or may be a cavity formed in one side of the button, as shown in Fig. 3.

It is obvious that various other articles can 55 be attached to flexible material in this way, such as glove-fastenings or lacing-hooks L, as shown in Fig. 4, and other devices.

I do not limit myself to the use of soft metal as a material for the pellet or body C. 60 If desired, said pellet or body may be composed of a compound or material which hardens from a plastic condition, such as papier-maché and other like materials; or the body C, instead of being a pellet, may be an eyelet 65 having a solid end or point which is inserted in the pocket of material, as shown in Fig. 5, and upset at its solid end, as shown in Fig. 6, by the same operation that upsets the tubular open end. 70

The improved method is adapted to various kinds of cloth, thin leather, and other material.

I am aware that it has been proposed to attach a hollow-shanked button of especial construction to material by inserting a pocket 75 into the shank of the button, and then compressing the end of shank to confine therein the ball and the pocket of material. Said method, however, is adapted only for use with the particular kind of button mentioned, while 80 mine is adapted to secure any plate or device that has two unobstructed sides and a perforation. 70

I claim—

1. The improvement in the art of attaching 85 buttons to garments, &c., consisting in inserting a portion of the fabric into the tubular or open part of the button, then placing a suitable compressible substance therein and flattening or expanding the same to force the enclosed fabric against the edge of the button-opening, as set forth.

2. The combination, of the button having an opening receiving part of the fabric and an expanded plug between which and the sides 95 of the opening the fabric is gripped, substantially as specified.

In testimony whereof I have signed my name to this specification, in the presence of two subscribing witnesses, this 18th day of August, 100 1882.

WILLIAM F. SPINNEY.
